to The Esterbrook Steel Pen Manufacturing Co.,
Camden, N. J., a corporation of New Jersey

Application October 12, 1937, Serial No. 72,138

Term of patent 14 years

To all whom it may concern:

Be it known that I, Leon Hehl Ashmore, a citizen of the United States of America and a resident of Collingswood, Camden County, New Jersey, have invented a new, original, and ornamental Design for a Combination Desk Unit or Similar Article, of which the following is a specification, reference being had to the accompanying drawing, forming part thereof.

In the drawing:

tion desk unit or similar article, showing my new design;

Fig. 2 is a plan view of the same, and
Fig. 3 is a front elevation.

I claim:

The ornamental design for a combination desk unit or similar article, substantially as shown.

LEON HEHL ASHMORE.
